UNITED STATES PATENT OFFICE.

WALLACE A. HAWLEY, OF NAPOLEON, MICHIGAN.

FENCE-MAKING MACHINE.

SPECIFICATION forming part of Letters Patent No. 399,040, dated March 5, 1889.

Application filed January 2, 1889. Serial No. 295,168. (No model.)

To all whom it may concern:

Be it known that I, WALLACE A. HAWLEY, a citizen of the United States of America, residing at Napoleon, in the county of Jackson 5 and State of Michigan, have invented certain new and useful Improvements in Fence-Making Machines; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to certain new and useful improvements in fence-making machines.

The object of my invention is to provide a simple, cheap, and effective portable apparatus which can be used for constructing picket-and-wire fences in the field.

20 My invention consists in the novel construction and combination of the parts, as will be hereinafter fully set forth and claimed.

25 In the accompanying drawings, Figure 1 is a side view of a fence-making machine constructed in accordance with my invention. Fig. 2 is a sectional view taken through the line *x x* of Fig. 1. Fig. 3 is a vertical section 30 through the line *y y* of Fig. 1. Fig. 4 is an end view. Fig. 5 is a detail view.

The frame of the apparatus consists of an upper horizontal beam, A, and corresponding lower horizontal beam, A', to the under side of 35 which is attached a shoe, *a*, the ends thereof being rounded. These horizontal beams are connected to each other by vertical beams B, B', B², B³, and B⁴, these parts together forming a rigid frame. The vertical beam B is 40 provided, to one side of its center, with three slotted openings, *b*, over which is secured by a bolt and nut, *b'*, an adjustable plate, C, which is provided with slots *b²* and *b³*, and also with perforations *c c*, through which the 45 wires pass. By raising or lowering this plate C the wires will be elevated or lowered and guided to the twister-heads. In the vertical beams B, B', and B² of the frame are openings 50 through which parallel horizontal bars D D pass, these bars being provided with heads *d*, which are adapted to lie within recesses formed in the vertical beam B², so that the

heads will lie flush with the outer edge of said beam when retracted. Embracing these bars D are clips or shackles *d'*, the threaded ends 55 of which pass through openings in a vertical coupling-bar, E, and are fitted with nuts, thus rigidly coupling said bars D together, but admitting of adjustment of coupling-bar forward or back on these bars D on loosening the nuts 60 on the clips *d'*. At opposite points on the coupling-bar E and beam B are pivoted the outer ends of toggle-arms *e* and *e'*, their inner ends being pivoted to each other and to a bar, E', the upper end of which passes through 65 a slotted opening, *e²*, in the horizontal beam A, and this bar E' is provided at a suitable point with a stop, *e³*, which contacts with the under side of the beam A to limit the upward movement of the bar. When the bar E' is 70 depressed, the rods D D are retracted, so that the heads *d* will lie within the recesses, and when elevated they will be projected or thrown out.

The bar E', hereinbefore referred to, is provided at a suitable point with an outwardly-projecting operating-handle, E², as shown in Figs. 2 and 3. The movement of the bars D D can be limited or varied by either adjusting the stop *e³* or by loosening the clips which 80 attach the bar E to said rods and moving said bar thereon.

The bar E is provided with an outwardly-projecting pin which passes through a curved slot, *f*, in one end of the lever F, which is pivoted to the vertical beam B', and to the opposite end of this lever, which is also provided with a short slot, is secured a movable bar, G, which passes through guide-openings near the ends of the horizontal beams A and A'. This 85 bar G is provided with two openings, *g g*, which are beveled from each side toward the center, and within these openings lie short crank-arms *h h*, which are rigidly keyed to the horizontal rock-shafts H H. These shafts H H 90 extend through the vertical beams B, B², and B³ of the main frame and have suitable bearings therein, and their ends *h'* are bent at angles to form downwardly and outwardly projecting hooks, the outer ends of which can be 95 thrown to extend beyond the edge of the beam B³ when the bar G is depressed, which is caused by elevating the bar E'. The opposite ends of the bars H H are screw-threaded and pro-

vided with suitable nuts to adjust them, so that hooks will be out a greater or less distance from the edge of the beam B^3 , as may be desired. When it is desired to adjust these 5 bars H , the keys which hold the arms h thereon will have to be loosened.

To the edge of the beam B^2 are secured spring-plates II , which serve to hold the picket in place by spring-pressure when placed between said plates. These spring-holders are made up of suitable plates of spring metal, which are bent at right angles, the outwardly-projecting portions thereof having their upper portions bent slightly outwardly, while 15 the downwardly-depending portions are bent slightly inwardly. The outwardly-projecting portions of the spring-plates are arranged to be on a line with the twister-heads.

The twister-heads, which are journaled between the vertical beams B' and B^2 , have between said beams sprocket-teeth, over which passes a chain, which is arranged, as shown, for operating said twister-heads and turning them in unison.

25 The center twister-head is provided with a beveled wheel, k , with which a beveled pinion, k' , meshes, said last-mentioned pinion being operated by a suitable crank-arm, k^2 , a bearing therefor being attached to the frame. 30 These twister-heads are provided with pipes or tubes $l l$, which are bent to converge or be near together at their front ends. Instead of these tubes being bent, they may be placed in the twister-heads at opposing angles, so as to 35 converge.

In constructing a fence of my improved apparatus three pairs of wires are first passed through the openings in the plate C and beam B . From thence they are passed through the 40 tubes $l l$ in the twister-heads and stretched between the posts, or between a post and tension device. The apparatus is then moved from the post a determined distance and the wires twisted to form a stop against which 45 the first picket will abut, and a picket or slat is slid between the pipes in the twister-heads and enters the spring-holders, so as to be retained in position. Then by raising the bar E' this slat or picket is moved toward the post 50 and forced snugly against the twist just made, after which the twister-heads are turned to twist the wires about said picket. When the bar E' is depressed, the rods will be retracted and the device is in position for inserting another picket. After the last-mentioned picket 55 is inserted between the holders the bar E' is raised, which will cause the rods $D D$ to move forward to drive the picket out of the holder I and up against the previously-made twist 60 in the wire, and as further movement of the picket is checked in that direction the continued movement of the toggle links or arms will cause the entire machine to move in the opposite direction until the hooks h' , which 65 have been thrown forward, engage the edge of the picket previously woven in and stop

further movement of the machine. This operation is continued until the fence is made, when the wires at the end are loosened and the machine removed. After the pickets 70 have been secured to the wires a suitable tension device may be employed for stretching the same.

It will be observed that by adjusting the bars H and correspondingly adjusting the 75 bars E the distance between the pickets can be varied.

With the hereinbefore-described device any form of twister-head may be used without departing from the spirit of my invention.

I am aware that prior to my invention twister-heads have been operated in unison by a chain, and I do not therefore claim such construction broadly; but

What I claim as new, and desire to secure 85 by Letters Patent, is—

1. In a fence-machine, the combination of the horizontally-supported rods $D D$, connected to each other to move in unison by a connecting-bar, a lever engaging with said connecting-bar so as to operate a vertically-moving bar to which rock-shafts are connected, the outer ends of said rock-shafts being provided with hooks, substantially as shown, and for the purpose set forth. 95

2. The combination, in a fence-machine constructed substantially as shown, of the parallel rods $D D$, connected to each other by a bar, E , which is adjustable thereon, a vertically-moving bar, E' , provided with links e 100 and e' , and a pivoted lever having one end slotted for engagement with the bar E , said lever being secured to a vertically-moving bar, G , with which projecting members of the rock-shafts II engage, the ends of said 105 rock-shafts being bent to form hooks or locks, substantially as shown, and for the purpose set forth.

3. The combination, substantially as described, of the supporting-frame, the horizontal bars $D D$, the coupling-bar rigidly secured thereto, the toggle-arms connected at their ends to the frame and coupling-bar, and centrally to a bar, E' , adapted to slide in vertical guides on the frame, and an adjustable 110 stop, e^3 , secured to said bar E' to limit the forward movement of bars $D D$. 115

4. The combination, substantially as described, of the twister-frame, the hooked rock-shafts journaled in said frame and threaded 120 at their inner ends, arms secured to said rock-shafts, a vertically-moving bar provided with openings to engage said arms, and nuts engaging the threaded ends of the rock-shafts to regulate the distance of the hooks from 125 the face of the frame.

5. In a fence-machine constructed substantially as shown, the combination, with the horizontally-moving bars $D D$, having heads, of a connecting-bar adjustably secured to said 130 rods and provided with an outwardly-projecting pin which passes through a curved

slot in a pivoted lever, F, the opposite end of
said lever engaging with a vertically-moving
bar for operating the rock-shafts H, so as to
throw, when the bars D D are projected, the
5 bent ends of the rock-shafts beyond the
frame to engage with a picket, substantially
as set forth.

In testimony whereof I affix my signature in
presence of two witnesses.

WALLACE A. HAWLEY.
